A. Brown,

Making Shoe Pegs.

No 22,061.

Patented Nov. 16, 1858.

UNITED STATES PATENT OFFICE

AZRO BROWN, OF WEST WATERFORD, VERMONT.

IMPROVED SHOE-PEG MACHINE.

Specification forming part of Letters Patent No. 22,061, dated November 16, 1858.

To all whom it may concern:

Be it known that I, AZRO BROWN, of West Waterford, in the county of Caledonia and State of Vermont, have invented a new and useful Improvement in Machines for Manufacturing Shoe-Pegs; and I do hereby declare that the following is a full, clear, and exact description of the same, reference being had to the accompanying drawings, making part of this specification.

Figure 1 is a front elevation of the improved machine. Fig. 2 is a longitudinal section of the same. Fig. 3 is a transverse section of the same at the line 1 2 of Fig. 1. Fig. 4 is a horizontal section of the same at the line 3 4 of Fig. 1.

Similar letters in the figures refer to corresponding parts.

The nature of this invention and improvement consists in, first, cutting from the bolt or block of wood thin strips corresponding in size with the length and thickness of the pegs to be formed and forcing them into radial slots formed in an intermittent rotating plate arranged between other plates or heads, on the faces of which next each other are formed projections, whose inner edges are made eccentric, helical, or spiral with the center, so as to operate upon the outer ends of the strips of wood above and below the radial slots in the intermittent rotating plate, and thereby force the whole series of strips of wood in the said slots toward the center at every intermittent motion of the said rotating plate the required distance to enable a peg to be cut from the end of each and all of them at every depression of a circular revolving knife, the required taper being previously given the pegs by stationary revolving knives, and the several operations necessary to this end being performed by a simple, compact, and novel series of parts arranged within a suitable frame.

To enable others skilled in the art to make and use my invention, I will proceed to describe its construction and operation.

The frame A is of a rectangular form, and is made of suitable size, strength, and material to contain and support the several parts of the machine. Longitudinally within this frame is arranged a horizontal shaft D, turning in boxes secured to cross-pieces of the same, on which are formed or secured cranks C, to which

are attached the lower ends of pitman-rods D, attached at their upper ends to the uprights E' of a cast frame E, which slide in grooves formed in uprights of frame F, erected on top of the main frame A. This cast frame E consists of the two uprights E', connected together by an arched and horizontally-extended cross-piece, to the apex or upper portion of the arched part of which is secured the upper end of a vertical shaft G, which extends downward below the base, from which said arched part is sprung, and is secured at its lower end to a cylindrical knife H, above which is arranged a circular plate I, projecting some distance beyond the periphery of the cylindrical knife H, and having secured in notches or spaces in its outer edge or periphery curved cutters J, which curve downward outside the circular knife H to within a short distance of the cutting-edge of the said knife H, and are made and shaped at their cutting ends in order to give the required taper to the pegs to be cut, as will be hereinafter stated. This circular plate I is secured to the lower end of a tube K, surrounding the vertical shaft G and having a band wheel or pulley L secured to its upper end, around which is passed a horizontal band extending also around a larger horizontal pulley M, secured on a vertical shaft N, turning in suitable boxes in the frames A F and having a cog-wheel or pinion secured near its lower end, which gears with cogs O, formed on the face of a drum P, secured on the end of the horizontal longitudinal shaft E. Motion is communicated to this drum P by a friction-wheel Q, secured on a horizontal shaft R, on the opposite end of which is secured a band-wheel S for receiving the band from the motive power which drives the machine. One end of this shaft R is suspended in a box secured on the end of a treadle-lever T, so as to enable the friction wheel or pulley Q to be forced against the periphery of the drum P with sufficient force to give motion to the same. A groove U is formed in the periphery of this drum P, near the edge of the same, which extends parallel to the said edges a little more than two-thirds of its whole circumference, and from the terminations of this parallel portion in a diagonal or zigzag course toward the opposite edge, somewhat after the manner and form of two cyma

reversas and cyma rectas joined, and in this groove U is inserted the lower end of a vertical bar V, attached at its upper end to near the end of a horizontal bar V', to the ends of which is secured a cross-head V², having grooved friction-wheels on its ends, which friction-wheels move in slots or between bars V³, secured on top of the frame A, for the purpose of guiding said bars and cross-heads in their longitudinal traversing movements. The horizontal bar V' is made about the same thickness of the pegs to be cut, and its opposite end passes between the faces of two vertical longitudinal knives W, secured parallel to each other on top of the frame A by having their thickened edges embedded and fastened in a slot formed in the same and situated the same distance apart as the intended thickness of the pegs to be cut. In front of the cutting-edges of these knives W and on a line with the same is arranged a table X, having vertical rods X' secured to its ends, which rods pass through openings in the top of the frame and a horizontal plank a short distance below, and are surrounded by spiral springs X² between the top of the frame and the said plank in such a manner as to enable the table to be depressed when desired. A hinged right-angled gage-bar Y is arranged on the opposite or rear side of these knives W, the forked ends of which bars are jointed to upright ears rising from the top of the frame A, while the gage portion rests in such relation and proximity to the cutting-edge of the rear knife W as to properly gage the bolt or block of wood to the two knives to properly cut the strip from the same of the required thickness.

Immediately above the edges of the knives W is arranged a longitudinal follower-block Z, secured to the lower ends of vertical parallel rods a, passing through the horizontal portions of the cast frame and surrounded between the upper horizontal portions by spiral springs b, the upper ends of which rest against the upper horizontal portion, while their lower ends are secured to projections on the rods a, or are secured to the said rods in any convenient manner, so as to enable the follower-block Z to yield when it is brought down upon the bolt or block of wood by the descent of the cast-frames, the extent of its yielding movement being regulated by adjusting-nuts c below one of the horizontal portions of the cast frame turning on screw-threads formed on the peripheries of the rods a below the spiral springs b.

On top of the frame A and immediately below the arched portion of the cast frame E and next the ends of the knives W is secured a circular plate d, having a rim at its periphery, on the upper edge of which is secured by screws a circular plate e. Within the space between these plates d e is placed another circular plate f, having a circular opening in its center corresponding in size with the cylindrical knife and having a series of radial

slots g in it extending from the center opening to the periphery and provided on its lower surface next the periphery with an increased thickness of body of metal, so as to form a circular shoulder or broad rim below the slotted portion, which fits in a corresponding circular depression or space in the upper surface of the lower plate d, an additional circular depression or gutter being formed in the said plate d next the rim for the reception of ratchet-notches h on the under surface next the outer periphery of the shoulder or rim portion of the slotted plate f. A segmental slot i is formed in the gutter or outer depression of the plate d, through which passes the end of a pawl k, jointed near its opposite end by a pin to the upper end of an oscillating lever l, whose lower end is connected by a rod m to near the lower end of the pitman-rod. The end of the pawl k which projects beyond the oscillating lever l is attached to the upper end of a spiral spring n, the opposite lower end of which is attached to the lower part of the oscillating lever l for the purpose of forcing the bent end of the pawl k against the ratchet-notches of the slotted plate f, and thereby enabling it to engage with said notches during one of its movements and to slip over the same upon its return movement, and to thus give an intermittent progressive motion to the said slotted plate f.

Immediately above the slotted plate f and between it and the rim of the plate d and the upper plate e, with which it corresponds in form on its outer edge and periphery, is secured a plate o, whose inner edge is made of a helical or spiral form commencing at the periphery of the space in the upper plate e just outside where the cylindrical knife W passes the same and extending entirely around the center in an eccentric course with the same and terminating at a radial slot p, formed in the plate o immediately opposite a corresponding narrow slot in the rim of the wheel or casting d, which is situated next the ends of the knives W and in continuation of the space between the same. On the upper surface of the plate d is formed a raised body, of metal, or ridge, whose inner edge q is situated immediately below the corresponding helical, spiral, or eccentric edge of the plate o, in order to bear against the ends of the strips of wood from which the pegs are formed as they are revolved in the slots in the plate f, the eccentric edge of the said revised part or ridge q on the plate d commencing at a point immediately below the point where the corresponding eccentric edge of the plate o commences, and gradually enlarging in its course round the center parallel with the said edge of the plate o, just mentioned, until it intersects the periphery of the depression in the plate d inside the outer gutter or depression.

The operation of this machine is as follows: The bolt or block from which the pegs are to be formed being placed on the table X, and by hand or other suitable means forced against

the gage-bar Y next to and slightly above the cutting-edge of the rear knife W, motion is communicated to the grooved drum P through the application of any suitable motive power to the band-wheel S on the friction-pulley-shaft R. This causes the cast frame E to be moved up and down at every revolution, and during this one and every revolution of the said drum P a strip of wood of the required thickness of the pegs to be cut from the bolt or block and a series of pegs corresponding in number to the number of slots in the slotted plate or wheel f, to be cut from the ends of the strips previously forced in said slots, and the said plate or wheel f to be rotated the extent of the distance apart of the slots, and the said strip cut from the block or bolt to be forced into the slot in the plate or wheel f, in which a previously-placed strip has just been cut into pegs in the following manner: We will suppose the cast frame E to be raised to the position represented in Fig. 2 and the edge of the block or bolt to be brought in contact with the edge of the gage Y. The revolution of the horizontal shaft B brings the cast frame E down by the action of the cranks, and with it of course the follower Z, which presses the block or bolt down with the table X, which yields for this purpose, and causes a strip to be cut from its end by the front knife and deposited in the space between the two knives W. During this descending movement of the cast frame E the revolving cylindrical knife H is caused to cut off a peg from each of the ends of the strips of wood in the slots of the plate or wheel f, and the angular cutters J on its sides cut out a corresponding-shaped channel in the upper edge of the whole series of strips at the required distance from the ends of the same to give the required taper to the peg to be cut off next in succession. After a series of pegs have thus been cut off by the cylindrical knife and discharged through the space or opening in the center of the plate or wheel e the cast frame E, with its attachments, rises, and the zigzag or curved portion of the groove v, having reached in its revolution the upright bar V, whose lower end is inserted in the same, operates on said bar V and gives it and the end of the horizontal bar V, to which it is secured, a traversing movement between the knives W and conveys the strip previously cut off and deposited in the spaces between them through the slot in the rim of the plate d and into the slot in the wheel or plate f, with which it communicates, a tapering or sharpened edge corresponding with the desired sharpness to be given the pegs being given it in its passage by the lower cutting V-shaped edges of an inclined adjustable stationary cutter y, secured by a set-screw z on top of the plate. Immediately after this strip of wood is forced into the slot and before the cast frame E reaches the full

extent of its upward movement, the spring-pawl acts against the notch (with which it is in contact) of the ratchet-notches on the slotted wheel or plate f and gives it the required intermittent motion to bring the next slot in succession opposite to and in immediate connection with the slot in the rim of the plate e. This motion of the slotted plate or wheel f causes the strips of wood in its slots to be revolved with it of course, and as their ends are moved past the eccentric helical or spiral edges of the plate and raised body or ridge of the plate they are forced toward the center, so as to cause their opposite ends, from which the pegs are to be cut, to project beyond the inner ends of the slots sufficiently far to enable the cylindrical knife H in its descent to cut off the series of pegs, as before described. In this manner the operation is continued, the slots in the wheel or plate f being filled and constantly replenished with fresh strips of wood from the block or bolt as the pegs are cut off therefrom by the action of the traversing bar V.

What I claim as new, and desire to secure by Letters Patent, is—

1. The combination and arrangement of the radial slotted plate f, eccentric helical or spiral edged plate, between which and the lower plate e it is confined, said lower plate e having depressions and gutters in its upper surface for receiving corresponding parts formed on the lower surface of the slotted plate f, and a raised or ridged portion nearer its center, whose inner edge corresponds with the eccentric curvature of the edge of the plate, the said slotted plate f and the other parts mentioned being arranged and operated substantially in the manner and for the purpose herein set forth.
2. Giving an intermittent progressive motion to the slotted plate f by the combination of the ratchet-notches on its under surface, spring-pawl K, and oscillating lever l, attached by a connecting-rod m to the pitman-rod, as before described.

3. Forcing or conveying the strips of wood from which the pegs are formed after being cut from the block or bolt by means of the combination and arrangement of the traversing bars V V', guided by wheels on the end of the cross-head at the angle where they are connected, curved groove U in the drum P, and knives W, between which the strip as first deposited and subsequently conveyed through the slot in the rim of the plate or rim e and under the V-shaped cutter V, substantially as herein set forth.

4. The combination of the cylindrical knife H and cutters J, as described.

AZRO BROWN.
